GEAR PUMP

Géza Walter Müller, Bron, France; vested in the
Alien Property CustodianApplication March 7, 1942, Serial No. 433,808
In France February 20, 1941

7 Claims. (Cl. 103—126)

The present invention relates to gear pumps and more particularly to such gear pumps as are used industrially for displacing viscous fluids, for example fluids of this category employed for spinning artificial textile filaments and threads, and as are generally interposed between a master pressure pump and the spinning dies, the chief function of such gear pumps being to regulate the rate of delivery of the fluid.

An object of the invention is to provide for the aforesaid and like uses a gear pump having such an improved construction as to fulfill practical requirements under better conditions than similar pumps as used heretofore.

Another object of the invention is to provide an improved gear pump the structure of which is so devised as to cause the whole of the fluid flowing therethrough to perform during operation lubrication of at least some of the revoluble members of the pump and particularly of the gear shafts.

Another object of the invention is to provide a gear pump having such an improved structure as to damp away the fluid pulsations, thereby enhancing the steadiness in the rate of flow of the liquid and ensuring better spinning conditions when said liquid is used for the production of artificial textile filaments or threads.

A further object of the invention is to provide a gear pump of such improved construction as to enable the fluid to circulate therethrough directly without being hindered or throttled and without any whirling or stopping effect, thereby avoiding such sedimentations as might otherwise clog up the circuit or interfere with proper spinning conditions.

A still further object of the invention is to provide an improved gear pump of simple and rugged construction particularly well suited for the handling of viscous liquids used in the production of artificial textile filaments and threads and comprising self-contained means ensuring automatic flushing lubrication by the liquid itself and at the same time great regularity of flow.

With these and such other objects in view as will incidentally appear hereinafter, the invention comprises the novel construction, combination and arrangement of parts that will now be described with reference to the accompanying diagrammatic drawings exemplifying the same and forming a part of the present disclosure.

In the drawings:

Figure 1 is a vertical sectional view showing in its entirety an improved gear pump according to the invention comprising a body plate hav-

ing recesses for the gears and side plates delineating and closing the pump body.

Figures 2 and 3 are elevational views showing the side plates.

Figure 4 is a side view showing the body plate separately.

Figure 5 is a diagrammatic elevational view showing the body plate, the other parts being omitted.

Figure 6 is a sectional view along the line X—X of Fig. 5.

Figure 7 is a sectional view of a modification of a detail of the pump.

Like reference characters designate like parts throughout the several views.

The constructional form of the invention illustrated in the drawings is a gear pump specially adapted for the handling of viscous liquids adapted to be spun into filaments or threads such for example as viscose, acetate, cupro-textile, artificial wool or the like.

Advantageously the pump body comprises a middle or body plate 1 formed with a pair of circular recesses 2 in which the gears 3 are snugly received. The middle plate 1 is closed and delineated sidewise by a pair of side plates 4, 5 through which are revolubly engaged the pins 6, 6₁ carrying the respective gears 3.

The side plates 4, 5 are hollowed to provide the suction duct 8 and the delivery duct 9 of the pump. The ducts 8, 9 preferably have their axes at right angles to the gear-carrying pins and have openings a, b, c, d which communicate with the holes in the side plates 4, 5 through which the pins 6, 6₁ are journaled.

Communication between the suction duct 8 and the suction chamber 18 of the pump takes place through a duct 10, a chamber 11 and a further duct 12. Likewise, communication between the delivery chamber 19 of the pump and the delivery duct 9 takes place through ducts 13, 14 and 15.

The chamber 11 is preferably formed in a separate front bracket 17, while the duct 14 is formed in a rear plate 16, said bracket and plate being bolted or otherwise fixedly secured to the side plates 4, 5 and pump middle plate 1.

As shown in Figs. 1 and 2, there is advantageously interposed on the delivery duct 9 intermediate the holes for the pins 6, 6₁ a ring or washer 20 having an annular groove 21 communicating with said duct 9. The ring or washer 20 may be axially bored to provide the duct 13 which communicates with the delivery chamber 19 of the pump and also with the duct 14.

The path of the liquid through the apparatus shown in the drawings is as shown by the arrows and may be described as follows:

The liquid sucked in by the pump enters the apparatus through the inlet aperture 22 and flows through the duct 8, then successively contacts or "licks" the front ends of the pins 6, 6₁ where they are journaled in the side plate 4. Thereafter the liquid enters the annular chamber 11 through the duct 10 and penetrates into the suction chamber 18 of the pump through the duct 12. The liquid forced out of the delivery chamber 19 enters the duct 14 through the duct 13 bored in the ring 20 and then penetrates into the duct 9 through the duct 15. After contacting and flushing the part of the pin 6 journaled in the side plate 5 and flowing through the groove 21 in the ring 20 (see Fig. 2) the liquid contacts or "licks" the part of the pin 6 journaled in the side plate 5 and is discharged through the outlet aperture 23.

It will be seen that the whole of the liquid moved by the pump can thus contact or flush both ends of the gear-carrying pins 6, 6₁ where they are journaled in the side plates 4, 5.

Alternatively, the following constructional arrangements may be adopted:

The gears 3 may be so mounted or splined upon their operating pins 6, 6₁ as to "float" upon them, the driving feathers 25 housed in said pins co-acting with grooves 26 formed in the bore of said gears 3 so that no axial thrust can be transmitted to these gears.

In order to provide for the required degree of liquid tightness on that side where the pin 6₁ is driven by the outer control shaft 27, elastic gasket 28 is provided so as to seal the chamber 11 on the front side. As shown in Fig. 1, said gasket comprises a U-shaped annulus and may be made for example of synthetic rubber.

Furthermore, owing to the fact that it contacts with the pumped fluid, said elastic gasket has the supplementary effect of damping the pulsations and of avoiding irregularities in the delivery flow from the pump.

In the constructional form shown, the gasket 28 is abutted against a washer 29 having a tight fit in a shouldered portion of the front bracket 17.

In order to improve said damping effect of the gasket 28, it is advantageous to provide the latter with grooves in one at least of the contact walls between said gasket and the washer 29. Preferably, these grooves having a suitable shape, for example a circular (grooves 28₁, Fig. 7) shape, will be situated in the bottom wall of said gasket 28.

The shaft 27 which may be connected to the pin 6₁ in any approved way drives the latter advantageously as illustrated in Fig. 1 owing to co-action between grooves 30 in the rear end of said shaft and a key or cotter 31 set through the pin 6₁. The sectional area of the key or cotter 31 is preferably reckoned so that in case of jamming or of any abnormal resistance occurring in the pump operation, said key or cotter 31 should be sheared, thereby protecting the rest of the mechanism against any such undue stress as might otherwise seriously damage the most costly parts of the apparatus.

In accordance with another alternative feature of the invention, the shaft 27 is independently lubricated, for example by means of a lubricator 32 having a screw-threaded reduced shank engaged through a hole tapped in the bracket 17, the extremity of said shank being in communication

with a groove 33 in said shaft so as to hold the latter in proper longitudinal position.

Moreover, according to a particularly advantageous arrangement, the suction chamber 18 and delivery chamber 19 formed in the middle plate 1 are defined by walls extending askew and generated by the intersection of an oblique cylinder (as shown in chain lines in Fig. 6) or a skew prism with the cylindrical recesses 2 in which the gears 3 are accommodated, the geometrical axis Y—Y of said cylinder or prism being situated in the plane of tangency X—X of the pitch circles e of the gears 3 and passing through the point of contact o of the pitch circles located in the mean plane of said gears. The degree of slant of those edges which define the suction chamber 18 and the delivery chamber 19 with respect to the gear teeth should be preferably so selected as to cause the nicks of two consecutive teeth to be continuously in communication with said chambers 18, 19. The purpose of this arrangement is to regularize the rate of delivery of the pump.

According to a further alternative constructional form, regularity of the rate of delivery may be still further improved (this being of the utmost importance for spinning) by interposing either on the suction duct or preferably on the delivery duct of the pump a second resilient damping member such as a rubber pad or stopper 34 arranged in the end of the duct 9 and providing for the resilient material of which it is made an accurately bored recess 35. Said stopper 34 is fitted on a cap plate 36 fixed to the side plate 5 by means of a screw 37.

It will be seen that owing to the foregoing construction, the several objects of the invention are fulfilled inasmuch as it becomes possible by simple and cheap manufacturing means to provide a self-lubricating gear pump using the pumped liquid as a lubricating medium and possessing great regularity of rate of liquid delivery, thereby ensuring a major advantage particularly where the pump is intended to feed liquid to spinning dies in the production of artificial textile materials.

Minor constructional details might be varied of course without departing from the ambit of the subjoined claims.

What I claim is:

50. 1. A gear pump comprising in combination a pump body constituted by at least a body part and a side part adapted to be juxtaposed to each other by one face, two recesses hollowed in said body part in said face, two pump gears housed in said recesses, holes in said parts, carrier pins for said gears journaled in said holes, one of said pins projecting outside the outer face of said side part, a fluid circuit through said pump, a bracket juxtaposed to said outer face of said side part, an excavation provided in said bracket, said excavation being adjacent to said outer face and coaxial with the projecting one of said carrier pins, a gasket of elastic material in said excavation, a path hollowed in said gasket round said carrier pin and forming a portion of said fluid circuit.

70. 2. A gear pump comprising in combination a body plate, side plates juxtaposed to the side faces of said body plate, two recesses hollowed through said body plate, two pump gears housed in said recesses, holes in said side plates, carrier pins for said gears journaled in said holes, one of said pin projecting outside the outer face of one side plate, suction and delivery chambers formed on either side of the intermeshing region

of said gears, a fluid circuit through said pump comprising suction and delivery ducts respectively in said side plates, each of said ducts being straight, openings for establishing communication between each duct and respectively each of the holes situated on the same side as the corresponding duct with respect to the gears, channel means connecting each of said ducts with respectively said suction and delivery chambers, a bracket juxtaposed to said outer face of said side plate through which a carrier pin projects, a circular excavation provided in said bracket, said excavation being adjacent to said outer face and coaxial with the projecting one of said carrier pins, a gasket of elastic material in said excavation having a path hollowed therein encircling said carrier pin and forming a part of the corresponding one of said channel means, and means journaled in said bracket for rotating said pump gears.

3. A gear pump comprising in combination a body plate, side bodies juxtaposed to the side faces of said body plate, two recesses in said body plate, two pump gears journaled in said side bodies for rotation in said recesses, means for driving said pump gears, a fluid circuit through said pump comprising suction and delivery ducts respectively in each of said side bodies and suction and delivery chambers in said body plate, said chambers being defined on either side of the intermeshing region of said gears by walls forming part of a slanting surface of revolution whose axis is sensibly contained in the plane of tangency of the gear pitch circles and passes sensibly through the point at which said circles contact in their mean plane, the angle of said axis with said mean plane and the radius of said surface of revolution being adapted so as to make each of said chambers communicate continuously at least with one nick between a pair of consecutive teeth. 40

4. A pump gear according to claim 1 further comprising grooves in the surface of said gasket by which the gasket contacts with the wall of said excavation.

5. A gear pump comprising a body plate having gear-receiving recesses and suction and delivery chambers located on either side of the gearing region, meshing gears housed in said recesses and having projecting carrier pins, a pair of side plates juxtaposed to the side faces of the body plate and so hollowed as to provide suction and delivery ducts, channel means establishing communication between the suction duct and chamber and between the delivery chamber and duct, the side plates having at right angles to their duct holes in which are journaled said pins, the peripheries of said holes being arranged so that the suction and delivery ducts are tangential thereto to cause the pumped fluid passing through said ducts to lightly lick and lubricate said pins. 10

15 6. A gear pump comprising a body plate having gear-receiving recesses therein, pump gears housed in said recesses and having projecting carrier pins, means for rotating said pump gears, and a pair of side plates on opposite sides of the body plate provided with apertures for journaling the projecting portions of said carrier pins, and also having suction and delivery ducts therein, said ducts being arranged tangential to said journal apertures whereby liquid passing through said ducts will lightly touch the periphery of said carrier pins while moving to and from the pump gears. 20

30 7. A gear pump as recited in claim 6, wherein resilient members are arranged in said ducts on opposite sides of said gears to cushion the flow of liquid. 35
